UNITED STATES PATENT OFFICE.

VERN F. ROBINSON, OF COPE, COLORADO.

LATCH FOR GATES.

Application filed May 9, 1922. Serial No. 559,540.

To all whom it may concern:

Be it known that I, VERN F. ROBINSON, a citizen of the United States, residing at Cope, in the county of Washington and 5 State of Colorado, have invented certain new and useful Improvements in a Latch for Gates, of which the following is a specification.

This invention relates to a latch for gates 10 and the like and has for its object to generally improve upon latches of this character by providing a device which will be of extremely simple, durable and inexpensive construction, one which is efficient and reliable 15 in operation, and well adapted to the purpose for which it is designed.

With these and numerous other objects in view, the invention resides in certain novel 20 features of construction, and the combination and arrangement of parts as will be hereinafter fully described and claimed.

In the drawing:—

Figure 1 is a perspective of a gate or door 25 and its frame showing my invention attached thereto,

Figure 2 is a vertical section taken therethrough,

Figure 3 is a horizontal transverse section taken on the line 3—3 of Figure 2 looking 30 in the direction of the arrow, and

Figure 4 is a detailed perspective of the latch mechanism.

Referring to the drawing in detail it will be seen that a door or gate 1 is hinged at 35 2 in the frame 3. All of these parts may be of conventional construction except that the free edge of the door 1 is notched as at 3'. The latch mechanism consists of a spring bar 4 having a curved extension 5 at its 40 upper end which terminates in an eye 6 to receive a screw or other like device 7 thereby holding the latch mechanism upon the door. This spring bar 4 is flat in construction being substantially rectangular in

45 cross section and terminates at its lower end in a U-shaped latch 8 which extends through the notch 3' of the door 1 and normally engages a keeper 9. The extension 10 on the U-shaped latch 8 passes through an eye or 50 sleeve 11 as does the lower portion of the spring bar 4 which is circular in cross sec-

tion. These sleeves 11 are carried by the bracket 12 which is suitably fixed adjacent the free edge of the door. An operating bail 13 is formed on the extension 10 and normally extends in a plane at substantially right angles to the door 1. There is an extension 14 on the bail 13 which extends through an opening 16 in the door. It will be seen that by pulling upon the bail 13 or 60 pushing upon the extension 14 the U-shape latch 8 may be fulcrumed from engagement with the keeper 9 and that the door may be readily opened. It will also be seen that the spring bar 4 normally keeps this latch 65 8 in engagement with the keeper when the door is closed.

From the foregoing description, taken in connection with the accompanying drawings, the construction and operation of the 70 device will be readily understood without a more extended explanation. As numerous changes in form, proportion, and in the minor details of construction may be resorted to without departing from the spirit 75 of this invention, I do not wish to be limited to the construction herein shown and described other than as claimed.

Having thus described my invention what I claim as new is:—

In combination, a door having a notch 80 in one edge, a bracket disposed on the door adjacent the notch and provided with a pair of spaced aligned sleeves, a latch mechanism including a spring bar flat in formation 85 fixed to the door and provided with an extension circular in cross section passing through one of the sleeves, a U-shaped latch formed by the extension and passing through the notch of the door, a second extension 90 formed on the latch and passing through the other sleeve, and operating means formed on the second mentioned extension so as to rotate the latch in the manner and for the purpose specified.

In testimony whereof I affix my signature in presence of two witnesses.

VERN F. ROBINSON.
